**TOOL FOR ASSEMBLING AND DISASSEMBLING
PIPES OR THE LIKE**

Beauford E. Steely, Dallas, and General L. Cranfill,
Friona, Tex., assignors to Cranford Corporation, Dal-
las, Tex.

Filed Oct. 23, 1965, Ser. No. 87,845

Term of patent 14 years

(Cl. D54—13)

FIG. 1

FIG. 2

FIG. 3

FIG. 1 is an end elevation of a tool for assembling and disassembling pipes or the like;

FIG. 2 is an elevation as seen from the left of FIG. 1; and

FIG. 3 is an elevation as seen from the right of FIG. 1.

We claim:

The ornamental design for a tool for assembling and disassembling pipes or the like, as shown.
